UNITED STATES PATENT OFFICE.

FRANK M. ZOTTOLI, OF BOSTON, MASSACHUSETTS.

TURBINE WHEEL.

Application filed December 3, 1921. Serial No. 519,753.

To all whom it may concern:

Be it known that I, FRANK M. ZOTTOLI, a citizen of the United States, residing at Boston, county of Suffolk, State of Massachusetts, have invented a certain new and useful Improvement in Turbine Wheels, of which the following is a specification, reference being had therein to the accompanying drawings.

10 The invention relates to new and useful improvements in turbine wheels. It is especially intended for application to turbine wheels which are mounted to turn on a vertical axis and are set in the midst of the current so that the current flows on both sides of the wheel. The special object of the invention is to provide an improvement in turbine wheels in which, although in the latter part of each revolution of the wheel, 15 that is in the return movement that portion of the wheel is rotating counter to the direction of flow of the current which drives the wheel, yet the resistance of the current to the return movement shall be much less than the pressure on the forward movement, and in fact reduced to almost nothing. Another object of the invention is to construct the wheel in such manner that it is adapted 20 for use both where the current is always running in the same direction, as in the case of a river, and also where the direction of the current reverses, flowing sometimes in one direction and sometimes in the reverse direction, as in the case of tides. Another 25 object of the invention is to provide means for increasing the power and velocity of the wheel.

One feature of the invention relates to the blades and consists in forming them of the floating character so-called; that is, having them pivoted to a central body so that the blades may yield to the resistance on the backward movement in the rotation and offer less resistance to the back pressure. 30 Another feature of the invention consists in providing a floating core or body to which the blades are attached. Another feature of the invention consists in providing deflecting walls on the exterior by which a current of water is deflected from a broader channel to a gradually decreasing width of channel until it strikes the blades thereby increasing the velocity and the force of the water until it reaches its maximum when it

strikes the blades. Another feature of the invention consists in providing the sluices between the deflecting walls with transverse ribs. Another feature of the invention is to so construct the blades and connect them with the body of the wheel in such manner that if a portion of the wheel projects above the surface of the water, the portion of the blades above the surface will be folded during the entire revolution of the wheel so as to still further reduce the resistance. Other features of the invention will be more fully set forth hereinafter in the specification and claims.

The invention will be fully understood from the following description when taken in connection with the accompanying drawings, and the novel features thereof will be pointed out and clearly defined in the claims at the close of this specification.

In the drawings, Fig. 1 is a horizontal sectional view of a turbine wheel and apparatus embodying the invention in the form intended for use at tide water, and operative when the tide is either ebbing or flowing, the wheel being shown in a position of rest.

Fig. 2 is a vertical section on line 2—2 of Fig. 1.

Fig. 3 is a diagrammatic view illustrating the application to a device set in tide water when the current is flowing.

Fig. 4 is a diagrammatic view of a modified form of construction of walls which is intended for use when the current is always flowing in the same direction.

Fig. 5 is a plan view showing the adaptation of the invention as embodied in a wheel connected with a float.

Fig. 6 is a diagram illustrating the application to a boat of a wheel embodying the invention.

Referring now to the drawings, there is provided a cylindrical drum 1 to which the blades 2 are connected, as will be herein-after described, said drum being intended to be mounted on a vertical axis and being preferably provided with a head 3 at its upper end and a head 4 at its lower end, so that it will be water-tight. The drum may, however, be open at the top, if not submerged. At its lower end it is provided with a downwardly extending vertical shaft or stud 5 which is journalled in a base or bed mem-

- ber 6, preferably also being provided with a washer 7. The drum is adapted to rotate on its vertical axis.
- At its upper end it is provided with an upwardly extending vertical shaft 8 journaled in an overhead bearing member 9. Said shaft 8 carries suitable mechanism for transmitting the power to the machinery which is to be driven.
- 10 The blades 2 which are curved as usual in turbine wheels, are each pivotally connected at 10 with the outer periphery of the drum 1. There is also provided on the outer periphery of the drum a series of shoulders 11 equal in number to the blades of the turbine so that there is a shoulder 11 provided against the back of each blade to serve as a stop to limit the swing of the blade on its pivot in the direction of the current pressure. As will be noted, however, the blade is free to turn on its pivot in the reverse direction. Preferably the pivoted end of the blade is rounded on an arc of a circle, as shown at 12, and fits into an arc-shaped seat 13 formed in front of the shoulder 11 so as to allow the blade to turn on its pivot with the least friction possible.
- Preferably each blade is made in sections, one above the other, as shown in Figure 2, 30 the lines 13 indicating the divisions between the vertical sections of a single blade. The purpose of this is so that if the turbine is only partially submerged in the water the several sections of the blade which are entirely above the surface of the water may be retained folded against the drum in the manner hereafter described during the entire revolution of the wheel, thereby reducing the amount of resistance which the blades 40 offer to the rotation of the wheel, while the submerged blades are spread open again when in the course of the rotation of the wheel the blades are travelling in the direction of the current.
- 45 The shaft 8 at the upper end of the drum is, as already stated, connected with suitable means for transmitting the power. In the form shown in the drawings, the shaft extends up through the bearing member 9 and its upper end is journaled in a second bearing member 14. Preferably washers 7 are provided where the shaft passes through the bearings 9 and 14. Intermediate the two bearing members 9 and 14 there are provided 50 transmission gears. Mounted on the shaft 8 is a ring gear 15 having teeth which engage with a gear 16 mounted on a horizontal driven shaft 17, which in turn may be connected with any apparatus which it is intended to drive. There is also mounted on said shaft 8 a bevel gear 171 which engages with the bevel gear 19 mounted on a driven shaft 20, so that one set of apparatus may be driven through the shaft 17 and another 60 set of apparatus may be driven through the shaft 20. It is obvious that only one driven shaft may be employed, if desired.
- Rising from the bed 6 on two opposite sides of the wheel and at some distance therefrom are the walls 21 and 22. The wall 21 70 has a branch portion 26 which sweeps around toward the wheel at the left hand side of the wheel as viewed in Fig. 1, terminating at the periphery of the circle described by the outer edges of the blades in the rotation of the wheel. The wall 22 has a portion 341 which sweeps around toward the wheel on the opposite side from the portion 26, said portion 341 terminating at the periphery of the circle described by the blades of the wheel. A 80 wall 29 which merges with the wall 21, forms, together with the wall 21, a converging channel for the water as it approaches the wheel from the right hand side. An intermediate wall 23 between the walls 21 and 29 divides the channel into two portions. The walls 23 and 29 form a converging passage for a portion of the water from the right hand side and direct the water at an angle against the blades on the front side of the wheel. The walls 21 and 23 form a sluiceway which directs the water against the blades at the side of the wheel almost all of the way around from the end of the wall 23 at the inlet side to the outlet side between the walls 25 and 28. 90
- Intermediate the walls 23 and 21 with its branch portion 26, there are provided a plurality of walls 27 which extend inwardly to the circumference of the circle described by the outer edges of the blades and extend outwardly into the space between the walls 23 and 21. Said walls 27 are arranged in converging relation to each other and form a series of short and narrow converging passages from the sluiceway between the walls 23 and 21 through which the water will be delivered against the blades in succession and at an angle thereto. 100
- A wall 25 which is connected with the wall 26 forms, together with the wall 22, an outlet passage for the water, assuming that the current is coming from the right hand side as viewed in the drawings. A wall 28 110 intermediate the walls 25 and 22 and corresponding with the wall 23 divides the main channel between the walls 25 and 22 so as to form two outlet passages, the main outlet being between the walls 25 and 28 which 115 diverge from each other toward the left, and if any of the water is carried past the wall 28 it will be discharged through the passage between the walls 22 and 28. 120
- If the apparatus is located in tide water 125 where the current reverses, then when the tide turns so that the current will be from left toward the right, as viewed in Fig. 1, the inlet will be between the walls 25 and 28 and between the walls 22 and 28 while the 130

sluiceways between the walls 29 and 23 will form the main outlet. A series of walls 30 similar to the walls 27 are provided between the wall 28 and the wall 22 and its branch 5 341 to aid in directing the water against the blades of the wheel when the current is from the left toward the right, as viewed in Fig. 1. Preferably there is a bend in the wall 21 at the point *a* and in the wall 22 at the point 10 *b* so as to deflect the water running through the passages both on the left and right sides of the wheel toward the wheel.

It will thus be seen that there are a series 15 of successive points in an arc of about 180°, that is, from the inlet around to the outlet side of the wheel, at which different currents of water will be directed against each blade.

The converging passages will increase the 20 velocity and force of the water.

The wall 25 is provided with a dog 31 pivoted to its inner end at 32, and the wall 29 has a similar dog 33 pivoted thereto at 25 34, said dogs each really forming a part of their respective walls 25, 29, the inner ends of the dogs coinciding with an arc of the circle described by the outer edges of the rotating blades 2.

When the current is flowing in the direction shown in Figure 3, that is, from right 30 to left, as indicated by the arrows, as soon as a blade begins to travel in a backward direction, it will be moving against the forward pressure of the current which, it will be understood, flows on both sides of the 35 wheel, and the forward pressure on the back side of the blade will turn the blade on its pivot causing it to be turned down toward the drum, thus offering less resistance to the forward pressure of the water than if the blade were rigidly connected with the 40 drum.

The forward pressure of the water when 45 moving in this direction will swing the dog 33 on its pivot into the position shown in Figure 3. The dog should be of the right spread so that when thus turned it will extend just about far enough radially inward for the blades in their folded position to sweep past it. The purpose of the dog is 50 to shut out to some extent at least the flow of the water through the passage traversed by the blades on the return movement, and thus diminish the back pressure on the blades. The other dog 31 will remain closed 55 as long as the current continues to flow. When the current reverses in direction from that shown in Figure 3, the dog 33 will be closed and the dog 31 will be opened.

The modified form shown in Figure 4 is 60 intended for use when the flow is always in one direction, as in the case of a river. The construction of the wheel itself is just the same as shown in Figure 1, the only difference being in omitting the duplicate 65 set of walls previously described for use

when the current flows in the opposite direction, and preferably bring the curved deflecting wall 26 somewhat further around, say about two-thirds, so as to be effective part way of the return path of the blades, 70 as shown in Figure 4.

In the forms already described, it is assumed that the apparatus will be set on the ground which forms the bed of the river or tide water wherever it is employed, 75 the bed plate and the walls in such case being heavy enough to remain in position by their own weight; for instance, the preferred method is to make them of concrete. As the water is of varying depth at different times, as by the rising and falling of the tide in tide water, or by varying heights in a river owing to natural causes, the blades are preferably made in sections, as 80 previously referred to, so that the sections which are entirely unsubmerged and therefore not exposed to the direct current may be allowed to lie idly folded against the drum so as to reduce the resistance which 85 they offer to the rotation of the wheel. 90

Instead of having the apparatus stationary on the bed of the stream or the sea, it may be mounted on a float so that it can rise or fall and thereby always be maintained in the same position with relation 95 to the surface of the water. In the form shown in Figure 5, there are provided floating side walls 134—134 which serve as a mount for the remaining portions of the apparatus. 100

The device is also adapted for use as a motor for a boat, as shown diagrammatically in Figure 6. In said figure, 35 represents a boat, having the turbine and its walls constructed as already described and as indicated at 36, secured to the bottom of the boat. The shaft 20 which is connected by suitable gearing with the vertical shaft 8 constitutes a propeller shaft carrying the propeller blades 37. The apparatus thus forms a motor to drive the boat which may be steered in any direction after the ordinary method of steering a boat. 110

A turbine constructed and used as I have described would preferably be made larger, 115 both axially and radially, than a wheel which is driven by a fall of water, as the current in a river or tide usually moves slower than falling water.

What I claim is: 120

1. In combination with a turbine wheel mounted on a vertical axis, a sluiceway in which said wheel is set, said sluiceway having two walls which form an entrance passage for the water, one of the walls of the 125 inlet extending along side of the wheel at some distance away from the sweep of the blades and then turning and extending to the periphery of the circle described by the sweep of the blades at a point just before 130

the outlet passage begins, whereby the full force of the free current will be directed against each blade in succession just before it reaches the point where the water passes 5 into the outlet channel.

2. In combination with a turbine wheel mounted on a vertical axis, a sluiceway in which said wheel is set open to tide water at each end, said sluiceway having walls 10 which form an entrance passage and an outlet passage for the tide water in whichever direction the current flows, one of the walls which form the entrance passage during the rising of the tide extending along 15 one side of the wheel at some distance away from the sweep of the blades and then turning and extending to the periphery of the circle described by the sweep of the blades at a point just before the outlet passage begins, 20 and one of the walls which form the entrance passage during the fall of the tide extending along side of the wheel at some distance therefrom on the opposite side of the wheel from the outer wall of the entrance 25 passage for the water on the rising tide, and then turning and extending to the periphery of the sweep of the blades at a point just before the outlet passage on the ebb tide begins, whereby the full force of 30 the free current will be directed against each blade in succession just before it reaches the point where the water passes into the outlet channel, in whichever direction the tide is flowing.

35 3. In combination with a turbine wheel mounted on a vertical axis, a plurality of walls arranged with their inner ends extending to the periphery of the wheel, two of the walls being so disposed as to form an inlet and two of the walls forming an outlet, 40 one of the pair of walls which form the entrance channel extending along one side of the wheel at some distance therefrom and then turning and extending to the periphery of the circle described by the outer edges of the blades, thereby directing the current of water against each blade in succession just before it reaches the outlet, said inlet channel extending substantially half way 45 around the periphery of the wheel at one side thereof until it nearly reaches the outlet channel, the inlet and the outlet channel walls being so disposed that the two 50 channels are offset in their direction with relation to each other.

4. In combination with a turbine wheel, a plurality of walls arranged in a series outside of said wheel, said walls being arranged with their inner ends extending to the periphery of the circle described by the outer edges of the blades of the wheel thereby forming a plurality of converging passages to the wheel, two of the walls on each of 60 two opposite sides being so disposed as to 65 form the side walls of a channel to con-

verge the flow of the water toward the wheel on one side and to diverge the flow after it has passed through the wheel on the opposite side and other converging walls in said series forming intermediate auxiliary 70 sluiceways.

5. In combination with a turbine wheel, a plurality of walls arranged in a series outside of said wheel, said walls being arranged with their inner ends extending to the periphery of the circle described by the outer edges of the blades of the wheel thereby forming a plurality of converging passages to the wheel, two of the walls on each of the two opposite sides being so disposed as to form side walls of a channel to converge the flow of the current toward the wheels on one side and to diverge the current after it has passed through the wheel on the opposite side and other converging 80 walls in said series forming intermediate auxiliary 85 sluiceways, the blades of said wheel being pivotally connected therewith in such manner that they are folded against the hub of the wheel in the return part of 90 the rotation of the wheel counter to the current, one of the main sluiceway walls having a pivoted portion adjacent the periphery of the circle described by the blades which is adapted to be turned back with its face 95 against the stationary wall and with one surface adjacent the periphery of the circle described by the rotation of the blades when the blades are in their normal, outer position and which is adapted to be turned on 100 its pivot so as to swing said pivoted portion transversely of the passage.

6. In combination with a turbine wheel mounted on a vertical axis, two vertical walls in converging relation to each other 105 which direct the flow of the water to the blades of the wheel at an angle thereto and whose inner ends extend to the periphery of the circle described by the blades in the rotation of the wheel, a third wall 110 which extends along one side of the wheel at some distance therefrom and then turns and extends to the periphery of the circle described by the outer edges of the blades in the rotation of the wheel and forms together with one of said first two walls another water passage, a plurality of short walls in said second passage arranged in a series in an arc of a circle, their inner 115 ends extending to the periphery of the path of movement described by the blades in their rotation, their outer ends extending only part way toward said outside wall, said short walls forming a plurality of passages to the blades of the wheel at an angle thereto and walls on the outlet side of the wheel forming an outlet passage for the water.

7. In combination with a turbine wheel mounted on a vertical axis, two vertical 120

walls in converging relation to each other which direct the flow of the water to the blades of the wheel at an angle thereto and whose inner ends extend to the periphery 5 of the circle described by the blades in the rotation of the wheel, a third wall which extends along one side of the wheel at some distance therefrom and then turns and extends to the periphery of the circle described 10 by the outer edges of the blades in the rotation of the wheel and forms together with one of said first two walls another passage for the water, a plurality of short walls in said second passage arranged in 15 a series in an arc of a circle, their inner ends extending to the periphery of the circle described by the outer edges of the blades in their rotation, their outer ends extending only part way toward said outside wall, 20 said short walls forming a plurality of passages to the blades of the wheel and walls on the outlet side of the wheel forming an outlet passage for the water, said outlet passage being offset in its direction with 25 relation to the direction of the inlet channel.

8. In combination with a turbine wheel mounted on a vertical axis, two walls which form a sluiceway extending along one side of the wheel, the outer of said walls extending farther forward than the inner one of said walls and having at its forward end a bent portion which extends around to the periphery of the circle described by the outer edges of the blades, the inner of said 30 walls extending to the periphery of the circle described by said blades but at a point nearer the approach end of the channel than the other wall, and a plurality of short walls intermediate the ends of said two first walls spaced apart from each other, whose inner ends extend to the periphery of the circle described by said blades at points between the inner ends of said two first walls, the outer ends of said second series of walls extending only partially across the 35 space between said two first walls. 40

9. In combination with a turbine wheel mounted on a vertical axis, two walls which form a sluiceway extending along one side of the wheel, the outer one of said walls 45 extending farther forward than the inner one of said walls and having at its forward end a bent portion which extends around to the periphery of the circle described by the outer edges of the blades, the inner of 50 said walls extending to the periphery of the circle described by said blades but at a point nearer the approach end of the channel than the other wall, and a plurality of short walls intermediate the ends of said 55 two first walls spaced apart from each other, whose inner ends extend to the periphery of the circle described by said blades at points between the inner ends of said two first walls, the outer ends of said second series of walls extending only partially across the space between said two first walls, said set of short walls being arranged in 60 converging relation to each other so as to form a plurality of converging passages to 65 the blades of the wheel at an angle to said blades. 70

In testimony whereof I affix my signature.

FRANK M. ZOTTOLI.
